UNITED STATES PATENT OFFICE.

JOSEPH SAMUEL CLICK, OF BRIDGEWATER, VIRGINIA.

PLOW.

No. 853,961.

Specification of Letters Patent.

Patented May 21, 1907.

Application filed July 3, 1906. Serial No. 324,678.

To all whom it may concern:

Be it known that I, JOSEPH SAMUEL CLICK, a citizen of the United States, residing at Bridgewater, in the county of Rockingham and State of Virginia, have invented a new and useful Plow, of which the following is a specification.

This invention relates more particularly to manually operated or so-called garden plows or cultivators, and one of the principal objects is to provide a structure wherein the weight and draft is placed as low as possible in order to overcome the top heaviness so noticeable in implements of this character.

15 A further and important object is to provide novel and simple means, whereby the plowing device may be made to properly operate in soils of different characters, and under varying conditions of use.

20 A still further object is to provide an extremely simple structure that can be cheaply manufactured, that is strong and durable and is easily adjustable to secure the most effective results.

25 An embodiment of the invention that is at present considered the preferable one is illustrated in the accompanying drawings and described in the following specification. An inspection of the claims hereto appended, will clearly show, however, that the invention is not limited to the structure set forth.

In the drawings:—Fig. 1 is a perspective view of the plow. Fig. 2 is a vertical sectional view thereof. Fig. 3 is a horizontal sectional view. Fig. 4 is a detail horizontal sectional view through the confection between the beam and standard.

Similar reference numerals designate corresponding parts in all the figures of the drawings.

40 In the embodiment illustrated, a beam is employed, comprising side bars 5, the main portions of which are spaced apart. The rear ends are preferably abutted, as shown at

45 6. In the present embodiment, these side bars are formed from a single piece, and are doubled, as shown in Fig. 4, but it will be evident that the bars may be separate pieces. The front end portions of the bars are upwardly curved, as shown at 7, and the front terminals 8 are turned rearwardly, being disposed directly over the main portions of the side bars. Openings 9 are formed in the rearwardly turned terminals, and are adapted to receive an axle, in the form of a belt 10, that can be placed in the different openings

9. This axle carries a spacing sleeve 11, on which is journaled the usual ground wheel 12 that operates between the side bars of the beam, and is adjustable with the axle. 60

A handle is employed, comprising handle bars 13 that converge toward their lower ends, and have said lower ends pivoted, as shown at 14 to the upwardly turned portions 7 of the side bars of the beam, the pivotal connections 14 being disposed in advance of and below the horizontal plane in which the axle of the wheel is located. The rear ends of the bars 13 carry a transverse handle bar 15 projecting beyond the bars 13, and having terminal grips 16.

A plow standard 17 is employed, which is preferably composed of bars or arms 18 that embrace the abutted rear ends of the beam bars 5, and are pivoted thereto, as shown at 19. The portions of the arms 18 below the beam, are suitably spaced apart, in order to receive the fastening bolt 20 of a suitable plowing or cultivating device, which may be of any desired character, and in the present 80 form, is shown as a tongue 21. The portions of the arm 18, above the beam, diverge and extend transversely of the handle bars. The upper portions of the side arms 18 are connected by a brace 22. The upper portions of the side arms are provided with series of openings 23, and the intermediate portions of the handle bars 13 are provided with longitudinal series of openings 24. Inasmuch as the handle bars 13 are pivoted, it 90 will be evident that they are capable of vertical swinging movement longitudinally of the side arms 18, and toward and from the beam, and in like manner, inasmuch as the standard is pivoted, it is also capable of swinging 95 movement longitudinally of the handle bars 13. These movements are ordinarily prevented, however, by bolts 25 that pass through certain of the openings 23—24, and maintain the parts against relative movement.

There are decided advantages for the structure disclosed. In the first place, it will be noted that the beam is disposed a considerable distance below the axis of rotation 105 of the wheel. This brings the weight comparatively close to the ground, and eliminates the top heaviness, which is so prominent a feature in many plows of this character. Moreover, the connection between the handles below the horizontal plane of the axis of rotation of the wheel brings the draft at a

comparatively low point, and as a result the plow is easier to operate. The adjustment of the wheel is desirable for if the ground is hard, and it is desired that the plowing device should enter the soil in a better manner, it is only necessary to adjust the wheel forwardly, thereby giving more power to force the plowing device into the ground, as it diminishes the tendency of the plow to balance over the hub. Moreover, it places the wheel farther from the shovel or other cultivating device, which in itself is an important feature under certain conditions. The peculiar construction and arrangement of the beam is also particularly desirable. In the first place, it will be observed that the beam itself constitutes the support for the handles, and eliminates the necessity for separate braces. Moreover, it permits the vertical adjustment 20 of the handle to the varying heights of the operators, who may use the plow. In addition to these features, however, it will be observed that by swinging the upper end of the standard toward or from the wheel, the plowing device may be made to assume different angles of inclination, and the different pitches thus obtained, insure the proper entry of the plow into the ground under different conditions.

30 From the foregoing, it is thought that the construction, operation, and many advantages of the herein described invention, will be apparent to those skilled in the art, without further description, and it will be understood that various changes in the size, shape, proportion, and minor details of construction may be resorted to without departing from the spirit or sacrificing any of the advantages of the invention.

40 Having thus fully described my invention, what I claim as new, and desire to secure by Letters Patent, is:—

1. In a plow, the combination with a wheel, of a plow beam connected to the wheel, and a handle connected to the beam in advance of the connection of the said beam with the wheel and below the horizontal plane in which said connection is located.
2. In a plow, the combination with a beam having an upturned portion, and a rearwardly turned front terminal carried by the upper end thereof, of a wheel journaled on the rearwardly turned terminal, and a handle connected to the upstanding portion of the beam below the horizontal plane of the journal axis of the wheel.
3. In a plow, the combination with a beam comprising side bars, having upwardly and rearwardly extending front end portions, of an axle connecting the upwardly extending portions, a wheel mounted on the axle, and handle bars connected to the upwardly extending portions of the side bars in advance of the axle and below the horizontal plane in which said axle is located.

4. In a plow, the combination with a beam of a handle connected to the front end thereof, and a wheel journaled on the beam in rear of the handle connection therewith and adjustable on the beam toward and from said front end and consequently toward and from said handle connection.

5. In a plow, the combination with a beam having an upwardly turned portion provided with a rearwardly turned terminal, of a handle connected to the upwardly turned portion, and a wheel journaled on the rearwardly turned terminal in rear of the handle connection and adjustable longitudinally along said rearwardly turned terminal toward and from said handle connection.

6. In a plow, the combination with a beam member, of a handle member, a plow standard pivoted to the beam member and adjustable to different angles of inclination with respect thereto, and connections between the standard and handle member for securing said standard against its pivotal movement and at said different angles of inclination.

7. In a plow, the combination with a beam member, of a handle member, and a plow standard mounted on said members and adjustable to different angles of inclination with respect thereto.

8. In a plow, the combination with a beam member, of a handle member, and a plow standard pivoted on one member and having an adjustable connection with the other member to hold said standard at different angles of inclination with respect to the beam.

9. In a plow, the combination with a beam, of a handle pivoted thereto, and a plow standard pivoted to the beam and having its upper end adjustable longitudinally along the handle, said handle being also adjustable longitudinally of the standard.

10. In a plow, the combination with a beam, comprising side bars, of a wheel journaled to and between the side bars of the beam, handle bars pivoted to the front portion of the beam, a standard pivoted between its ends to the rear portion of the beam, means for securing a plowing device to the lower side of the standard, the upper portion of said standard comprising spaced arms disposed in transverse relation to the handle bars, said standard arms and handle bars each being adjustable longitudinally along the other, and means for securing them against relative movement.

11. In a plow, the combination with a beam, comprising spaced side bars having upwardly and rearwardly turned front ends, of a wheel journaled on the rearwardly turned portions and adjustable along the same, handle bars pivoted to the side bars of the beam, the pivot connections being disposed below the horizontal plane of the wheel connection, a plow standard pivoted between its ends

upon the rear end of the beam and comprising spaced side arms, the upper ends of which are disposed transversely of and are slidable longitudinally along the handle bars, said handle bars being also movable in a substantially upright direction upon the side arms, and means for connecting the side arms and handle bars to secure the standard against movement.

10. 12. In a plow, the combination with a beam having an upturned front portion, of a

wheel journaled on said upturned front portion and having its axis of rotation disposed above the main portion of the beam, and a handle connected to said beam. 15

In testimony, that I claim the foregoing as my own, I have hereto affixed my signature in the presence of two witnesses.
